AUTOMATIC POSITIONING MEANS

Herbert Harvey and Ralph S. Thacker, Los Angeles, Calif., assignors to Leo M. Harvey, La Canada, Calif.

Application July 26, 1941, Serial No. 404,180

12 Claims. (Cl. 192--135)

This invention relates to controls and relates more particularly to a control or means for operating and controlling moving machine elements. A general object of this invention is to provide a system or means of this character which automatically brings the moving element to a given or selected position each time operation of the element is terminated.

In machines and devices of various kinds it is often desirable to cause a moving part to come to rest in a given or known position each time it is to be stopped. For example, in commercial washing machines it is highly desirable to bring the rotating cylinder to a given position at the completion of the washing operations. In commercial washing machines the clothes are placed in a perforated rotatable tumbler or cylinder which in turn operates in a shell containing the water, washing mixtures, etc. The surrounding shell and cylinder have openings through which the articles being washed are passed and these openings have suitable doors. To facilitate the loading and unloading of the cylinder it is necessary to bring the cylinder to a position where its opening communicates with the opening of the shell and it is highly desirable to bring the openings into perfect or substantially perfect registration to facilitate the safe operation of the doors and to prevent the clothes or materials from being caught between the cylinder and shell. In the washing machines now in general use the cylinder may stop in any position at the conclusion of the washing operations and the operator is obliged to employ inching switches to inch or shift the cylinder to the correct position by successive stages. This inching operation is tedious, time consuming and unsatisfactory for obvious reasons.

An important object of this invention is to provide dependable, efficient and entirely automatic means for accurately positioning a moving or rotating element in a selected or known position each time movement or operation of the element is terminated.

A more specific object of this invention is to provide means for automatically positioning the rotatable cylinder of a commercial washing machine where its access door is in registration with the door of the shell each time operation of the cylinder is terminated. The automatic positioning means of the invention operates to bring the cylinder door into registration with the door of the shell regardless of what position the cylinder happens to be in when the operator

or a control mechanism acts to discontinue cylinder operation.

Another object of this invention is to provide a positioning means of the character referred to that is accurate and rapid in operation, bringing the cylinder or moving part to the required position with a minimum range of possible inaccuracy and in the shortest time possible. The cylinder or moving part is always stopped with its access opening and door within a very few inches, say, from 1 to 3 inches of exact registration with the shell door without "hunting" or time consuming back and forward movements of the cylinder.

Another object of this invention is to provide an automatic positioning means of the character mentioned which operates with the same accuracy and speed regardless of the direction the cylinder may be moving or turning when cylinder operation is discontinued. The control is entirely successful and fully operative in installations where the cylinder or moving part alternately turns in the right and left hand directions or moves back and forth during normal operation.

Another object of this invention is to provide a positioning means of the character referred to that always produces final movement of the cylinder in a given direction, which I will term the "up" direction, to bring the cylinder to the door registering position so that the clothes or materials in the cylinder are in the most advantageous position for removal when the cylinder is stopped.

Another object of this invention is to provide a positioning means of the character referred to that may be used with a manually operated control such as a manually operated switch for terminating cylinder operation or may be used with an automatic control such as the automatic cycle governing mechanism employed in commercial washing machines for timing the operation of the cylinder and other elements of the machines.

The various objects and features of the invention will be fully understood from the following detailed description of a typical preferred form and application of the invention, throughout which description reference is made to the accompanying drawing, in which:

The drawing is a wiring diagram of the circuits embodied in the invention with certain parts of a washing machine and certain elements of the control mechanism illustrated in a diagrammatic manner.

The present invention has many uses or applications and may be varied considerably to adapt it for different installations. In the following detailed description we will describe the invention associated with a commercial washing machine to automatically position the cylinder of the machine at the termination of each operation of the cylinder. It is to be understood that the invention is not to be construed as limited or restricted to the specific form or application about to be described but is to be taken as including any features or modifications that may fall within the scope of the claims.

The portion of the washing machine illustrated includes a stationary shell 10 adapted to contain the washing mixtures, water, bleaches, etc., employed during the successive operations. A suitable opening 11 is provided in the wall of the shell 10 in a position where it is accessible to the operators and the opening is closed by a door 12 when the machine is in operation. A hollow perforated cylinder 13 is rotatable within the shell 10. The cylinder 13 is provided to receive and contain the clothes or articles to be washed and has the usual lifting ribs 14 to lift and tumble the clothes. An opening 15 is provided in the wall of the cylinder 13 through which the clothes or materials are inserted and removed and the opening 15 is closed by a suitable door 16 when the machine is in operation. The cylinder 13 is supported in concentric relation to the shell 10 for rotation therein and is driven by a shaft 17 which in turn is operated or driven by a reversible motor M.

The mechanism or system of the present invention may be said to comprise, generally, a normally operative control 20 for the cylinder motor M, switch means A, B and C operated by the cylinder 13, a relay 21 under the control of the switch means A, B and C and a stop switch 22 adapted to be operated either manually or by an automatic timer and operable to cut out the normally operative control 20 and to cut in the relay 21 so that the switch means A, B and C is rendered operative to position and stop the cylinder 13.

The normally operative control 20 may be such as to cause continuous or uninterrupted rotation of the cylinder 13 in one direction during the period of cylinder operation or may be operable to cause alternative right and left hand rotation of the cylinder during this period. In the case illustrated, the control 20 is of the latter type, serving to cause rotation of the cylinder 13 to the right, then to the left, then to the right, and so on, throughout the duration of cylinder operation. The motor M is reversible and is supplied with operating current by a three wire power circuit 1-2-3. The reversible motor M is operable to rotate the cylinder in the right hand and left hand directions which I will herein refer to as the "up" and "down" directions, respectively, and which are so designated in the drawing. The normally operative control 20 includes "up" and "down" relays 23 and 24 connected in the power circuit 1-2-3 to produce forward and reverse operation of the motor. The "up" relay 23 includes three pairs of contacts 23^a, 23^b and 23^c connected with the three power wires 1, 2 and 3, respectively, and the "down" relay 24 has corresponding pairs of contacts 24^a, 24^b and 24^c which are connected in the divided power circuit in the order 3-2-1, that is, the contacts 24^a are connected with the wire 1, the contacts 24^b are connected with the

wire 2 and the contacts 24^c are connected with the wire 3. Common leads 25, 26 and 27 extend from the "up" and "down" relays 23 and 24 to the motor M. The lead 25 is connected with the stationary contacts 23^a and 24^c, the lead 26 is connected with the stationary contacts 23^b and 24^b, while the lead 27 is connected with the stationary contacts 23^c and 24^a. The relays 23 and 24 further include operating coils 28 and 29, respectively, for opening and closing their respective pairs of contacts. With the contacts of the "up" relay closed the cylinder 13 is rotated in the up direction as indicated in the drawing and when the contacts of the "down" relay 24 are closed the cylinder 13 is rotated in the down direction.

The normally operative control 20 further includes an automatically reversing timer for controlling the coils 28 and 29 of the "up" and "down" relays 23 and 24. This reversing timer may be of any well known type. In the present case it may be considered as comprising a double throw switch 30 whose blade or movable element 31 is connected in one side or lead 32 of a power line. The other side or lead 33 of the power circuit extends directly to one pole of each of the coils 28 and 29. A line 34 extends from the second terminal of the coil 29 to one contact 35 of reversing switch 30 and a similar line 36 extends from the second terminal of the coil 28 to the other stationary contact 37 of the reversing switch. As diagrammatically illustrated, the blade 31 is spring biased or operated toward the contact 35 by a spring 38 and is operated in the other direction to engage the stationary contact 37 by a winding or coil 39. The coil 39 is connected in the power line 32 and the power line 32 is controlled by a suitable make and break mechanism 40 so that the coil 39 is energized during given periods and is deenergized during the intervals between these periods. The make and break mechanism 40 may be driven by the motor M and may be of any selected character. For this reason the details of the mechanism 40 have been omitted from the present disclosure.

The switch means A-B-C governs the motor M through the medium of the relay 21 to position and stop the cylinder 13 where its opening 15 is in registration with the shell opening 11. The switch means A-B-C comprises a cam or part 42 movable with the cylinder 13 and the three spaced switches A-B-C are controlled or operated by the cam. The cam 42 may be mounted in any selected manner to rotate with the cylinder 13. In the case diagrammatically illustrated the cam 42 is at the periphery of the cylinder 13, it being understood that this is merely illustrative and that in most instances it is preferred to arrange the cam 42 at the exterior of the shell, for example, on a sprocket, wheel or other part secured to the cylinder 13 or shaft 17. The cam 42 is of substantial circumferential length, its length being dependent upon the spacing of the switches A and B and upon other factors as will later become apparent. The opposite ends of the cam 42 incline or slope up to the crest of the cam which is concentric with the axis of rotation of the cylinder 13. The switches A, B and C may be of any selected type suitable for operation by the cam 42. It is preferred to employ switches A, B and C that operate with slight movement and that are positive.

The switch A may be termed the "condition switch" as it conditions the relay 21 for the cyl-

inder positioning and stopping operation. The switch A comprises an inner pair of contacts 43 and 44, an outer pair of contacts 45 and 46 and a contactor 47 movable between an in position where it electrically connects the contacts 43 and 44 and an out position where it electrically connects the contacts 45 and 46. The contactor 47 is normally in the in position in cooperation with the contacts 43 and 44, as illustrated, being spring urged or gravity urged to this position. The contactor 47 is arranged to be moved outwardly by the cam 42 to the out position where it is clear of the contacts 43 and 44 and where it electrically connects the contacts 45 and 46.

The switch B is the "stopping switch," serving to deenergize the motor M and cause operation of a brake 48 associated with the motor M. In accordance with the invention the switch B is spaced forwardly from the switch A relative to the up direction of rotation of the cylinder 13. The switch B includes a pair of contacts 49 and 50 and a contactor 51 adapted to electrically connect the contacts 49 and 50. The contactor 51 is arranged to be operated outwardly by the cam 42 to a position clear of the contacts 49 and 50. The contactor 51 is normally in cooperation with the contacts 49 and 50, being spring or gravity urged to its in position. The space between the contactors 47 and 51 of the switches A and B is greater than the effective length of the cam 42 so that the cam cannot "bridge" the two contactors to cause simultaneous operation of the switches A and B but the distance between the contactors 47 and 51 need not be more than a few inches greater than the length of the cam.

The switch C may be termed a "safety switch" as it serves to assure correct operation of the system in the event the stop switch 22 is operated in the same time the cam 42 is holding the contactor 47 of the switch A in its out position during "down" rotation of the cylinder 13, which occurrence would otherwise result in continuing rotation of the cylinder. The switch C may be similar to the switch B, comprising a pair of contacts 52 and 53 and a shiftable contactor 54 engageable with the contacts to electrically connect the same. The contactor 54 may be spring or gravity actuated to the in position where it cooperates with the contacts 52 and 53 and where it is adapted to be moved out of engagement with the contacts by the cam 42. The switch C may be located at any selected point in the path of the cam 42 except in that zone lying between the switches A and B or the zone immediately on the "down" side of the switch A. In practice it may be preferred to space the switch C some distance from the switch A as illustrated.

The brake 48 is provided to stop the cylinder 13 when movement of the cylinder has been greatly retarded by the action of the positioning system and serves to hold the cylinder in the position where the opening 15 is in register with the opening 11. The brake 48 may be associated with the motor M and may comprise a plate or disc 55 fixed to the shaft 17 and a similar disc 56 slidable on the shaft 17 and equipped with friction material for contacting the disc 55. A lever 57 has one end operatively connected with the disc 56 and its other end pivotally connected with the armature or shiftable element 58 of a solenoid coil 59. A spring 60 is arranged under compression between the shiftable disc 56 and a stationary abutment and tends to force the disc 56 against the disc 55 to produce the braking effect. The solenoid 59 of the brake 48

may be connected in the operating circuit of the motor M to remain energized so long as the motor M is energized. In the drawing one lead 61 of the solenoid 59 is connected in the motor lead 26 and the other lead 62 of the solenoid 59 is connected in the motor lead 27. With the solenoid 59 energized during energization of the motor M the solenoid 59 holds the lever 57 in the position where the disc 56 is clear of the disc 55, as shown in the drawing. When the motor M and the solenoid 59 are deenergized the spring 60 forces the disc 56 into engagement with the disc 55 to stop movement of the cylinder 13 and to hold the cylinder against further movement.

15 The relay 21 is put into operation when the cam 42 moves the contactor 47 of the switch A into engagement with the contacts 45 and 46, assuming the stop switch 22 has been operated, and the relay thereupon serves to govern the motor M in such a manner that the cylinder 13 is stopped when the cam 42 comes into cooperation with the switch B. The relay 21 includes a solenoid 63, three movable contacts 64, 65 and 66 controlled by the solenoid 63 and three stationary contacts 67, 68 and 69 engageable by the movable contacts 64, 65 and 66, respectively.

20 The movable contact 64 is connected to the power line 32 by a lead 70 and a line 71 extends from the mated stationary contact 67 to the contact 45 of switch A and has an extension 72 continuing from the contact 46 of switch A to the lead 70 or the power line 32. A line 73 extends from one terminal of the solenoid 63 through the switch C to lead 71 and a lead 74 extends from the other terminal of solenoid 63 to the power line 33. It will be seen that upon operation of the contactor 47 by the cam 42 that a circuit will be temporarily completed through the line 73, the switch C, the line 71, the contacts 45 and 46 and the line 72 to the power line 32 and through the lead 74 from the other power line 33 to the other terminal of the solenoid 63. Thus, the relay 21 is energized upon outward movement of the contactor 47 of switch A. Energization of the solenoid 63 brings the contact 64 against contact 67 and a sustaining circuit for the solenoid 63 is completed through the lead 70, the contacts 64 and 67, the lead 71, the switch C and the lead 73. From the above it will be seen that engagement of the cam 42 with the contactor 47 of the switch A will put the relay 21 into operation assuming the stop switch 22 has been operated, as will be later described.

25 The relay 21 is operable to cause energization of the down relay 24 of the motor circuit so that the motor M may act as a retarding means or brake to lessen the rate of movement of the cylinder 13 in the event the cylinder 13 is turning in the "up" direction. As above described, the lead 34 extends from one terminal of the coil 28 of "down" relay 24 to the reversing switch 30 for connection therewith by the power line 32. The other power line 33 may be directly connected with the other terminal of the coil 29. When the stop switch 22 is operated, as will be later described, the reversing switch 30 is cut out and the solenoid 29 of the "down" relay 24 is put under the control of relay 21. A lead 75 extends from the lead 34 to the stationary contact 68 of relay 21. A line 76 extends from the cooperating movable contact 65 of relay 21 to the contact 50 of switch B. A branched or common lead 77 connects the contacts 49 of switch B and 44 of switch A with the above described lead 72. When the relay 21 is energized a circuit is completed

through the coil 29 of the "down" relay 24 through the leads 34 and 75, the contacts 68 and 65, the lead 76, the closed switch B, and the leads 77 and 72. In this connection it will be observed that the switch B is interposed in the energizing circuit of the coil 29, that is, the circuit of the coil 29 which comes into use following operation of the stop switch 22 and the switch A.

The relay 21, prior to its energization and subsequent to operation of the stop switch 22, completes a circuit to the coil 28 of the "up" relay 23 and when the relay 21 is energized or operated the circuit to the "up" relay 23 is broken. One terminal of the "up" relay coil 28 is directly connected in the power line 33 and, as above described, a line 36 extends from the other terminal of the coil 28 to the reversing switch 30. A lead 78 extends from the lead 36 to the stationary contact 69 of relay 21. A lead 79 extends from the movable contact 66 of relay 21 to the contact 43 of switch A. The above mentioned lead 77 is connected with the other inner contact 44 of switch A so that contact 44 is in electrical connection with the power line 32. Accordingly, in the event the stop switch 22 is operated when the cylinder 13 is moving in the "up" direction, the circuit to the up relay 23 is maintained and the cylinder will continue to rotate in this direction. As will later become apparent, operation of the stop switch 22 to terminate operation of the cylinder 13 results in disconnection of the down relay 24 from its energizing circuit and closes the circuit to the solenoid 28 of the "up" relay 23 through the line 78, the contacts 66 and 69, the lead 79, the switch A and the leads 77 and 72.

The stop switch 22 may either be a manually operated switch or a switch automatically controlled by a timer or other automatic means. When the stop switch 22 is operated from the normal position where the cylinder 13 is in operation to the position illustrated in the drawing the switch transfers the control of the motor M from the relays 23 and 24 to the relay 21. The stop switch 22 is interposed in the power line 32, having movable contact 80 and a stationary contact 81 connected in the line 32 ahead of the reversing switch 30. When the movable contact 80 is in engagement with the contact 81 the circuit is completed through the lead 32 and the reversing switch 30 to the relay 23 or 24, as the case may be, and the make and break mechanism 40. The stop switch 22 includes a second stationary contact 83 forming the terminal of the above described leads 70 and 72. When the movable contact 80 is brought into cooperation with the contact 83, the circuit to the coil 29 of the down relay 24 is broken because the reversing switch 30 is no longer effective and the circuit to the coil 28 of the "up" relay 23 is completed through the normally closed contacts 66 and 69 of the relay 21 so that the cylinder 13 is made to continue to rotate in the "up" direction in the event it is already turning in that direction or is made to turn in the "up" direction in the event that it has been turning in the "down" direction.

In the operation of the system it will be first assumed that the stop switch 22 is operated from its normal position to the position illustrated in the drawing at a time when the cylinder 13 is rotating in the "up" direction. In this event, the reversing switch 30 is cut out so that the make and break mechanism 40 is no longer operative in causing alternate up and down rotation of the

cylinder 13. Operation of the stop switch 22 closes a circuit to the coil 28 of the "up" relay 23 through the line 72, the lead 77, the switch A, the lead 78, the normally closed contacts 66-69 of relay 21 and the leads 78 and 36. Accordingly, "up" rotation of the cylinder 13 continues and is assured until the cylinder is brought to a stop. Rotation of the cylinder 13 brings the cam 42 into cooperation with the contactor 47 of switch A. Operation of the contactor 47 by the cam 42 breaks the above described circuit through the normally closed contacts 66 and 69 of relay 21 to the up relay coil 28 and temporarily completes a circuit to the coil 63 of relay 21. This temporarily completed circuit comprises the lead 74 to one terminal of the coil 63, the lead 73 extending through switch C, the lead 71 extending to contact 45 of switch A and the lead 72 extending from contact 46 of switch A to the stop switch 22 which connects it with the other side 32 of the power line. Temporary or momentary operation of relay 21 resulting from momentary operation of switch A by the cam 42, as just described, completes a sustaining circuit to the coil 63 of relay 21. The sustaining circuit of the coil 63 includes the lead 74 extending from one power line 33 to the coil 63, the lead 73 extending from the coil 63 through the switch C to lead 71, the engaged contacts 64 and 67, and lead 70, which is connected with the other power line 32 by the operated stop switch 22. Thus, it will be seen that operation of the switch A by the cam 42 first produces momentary energization of relay 21 and this in turn results in sustaining of the relay 21 through the circuit just described.

With the coil 63 of relay 21 operated the circuit to the "up" relay coil 28 is broken and a circuit is completed to the coil 29 of the "down" relay 24 through the switch B. With the coil 63 energized the contact 68 is out of engagement with the contact 69 so that the circuit to the coil 28 of the "up" relay 23 is broken. So long as the coil 63 of relay 21 is energized a circuit is completed through the coil 29 of "down" relay 24 through the leads 34 and 75, the made contacts 68 and 65, the leads 76, the switch B, the lead 77, the lead 72 and the stop switch 22 which connects lead 72 with power line 32. When the "up" relay 23 is deenergized, as just described, the motor M is energized and serves to retard, brake or slow down the "up" rotation of the cylinder 13. The cylinder 13 is usually quite heavy and usually contains a mass of wet clothes, or the like, and thus has substantial inertia. The braking or retarding action of the reversed motor M slows the rotation of the cylinder 13 but the inertia of the cylinder carries the cylinder on so that the cam 42 moves from the switch A to the switch B. However, by the time the cam 42 reaches the switch B the cylinder 13 is turning at a very slow rate.

When the cam 42 operates the contactor 47 outwardly from the stationary contacts 49 and 50 the circuit to the coil 29 of the "down" relay 24 is broken, this circuit having been followed in detail above. Opening of switch B by the cam 42 results in complete deenergization of the motor M and the brake coil 59, the "up" relay coil 28 having been deenergized upon energization of the relay 21, as above described. Upon deenergization of the coil 59 the spring 60 operates the brake disc 56 against the disc 55 and the cylinder 13 is stopped. The cylinder 13 is turning at a

very slow rate and with little inertia when the brake means goes into operation and the brake means 48 is effective in stopping the cylinder 13 in the position where the cam 42 holds the switch B open. Further, and of particular importance, is the fact that the brake means 48 stops the cylinder 13 in a position where its opening 15 is in registration with the opening 11. The spacing of the switch B from the switch A and the proportioning of the cam 42 assures the stopping of the cylinder 13 in the position where its opening 15 is in register with the opening 11 of the shell 10.

It is to be understood that the stop switch 22 is retained in the position illustrated in the drawing for a given period, either mechanically or manually, during the above described cylinder stopping operations. In actual operation this period in which the switch 22 is held in the position illustrated is relatively short as the cylinder stopping and positioning operations above described require only a short time for their completion, but these operations vary slightly depending upon the position of the cam 42 at the time of reversal or operation of the stop switch 22.

It will now be assumed that the washing machine is in operation and that the switch 22 is operated from its normal position to the position illustrated at a time when the cylinder 13 is turning in the "down" direction. As above described, operation of the stop switch 22 to the position illustrated in the drawing disconnects or cuts out the coil 29 of the "down" relay 24 because the lead 34 from the coil 29 is connected with the power line 32 through the reversing switch 30 and the operated stop switch 22 cuts out the reversing switch 30. Operation of the stop switch 22 to the position illustrated also serves to complete a circuit to the coil 28 of the "up" relay 23 through the leads 36 and 78, the normally closed contacts 66-69 of relay 21, the lead 79, the switch A, the leads 71 and 72 and the stop switch 22, the stop switch 22 being coupled with one side 32 of the power line and the other side 33 of the power line being coupled with the coil 28. Operation of relay 23 reverses the motor M and causes the cylinder 13 to reverse its direction of rotation, that is, to turn in the "up" direction instead of the "down" direction. The cam 42 may be at any rotative position when the reversal of direction of rotation of the cylinder 13 occurs.

In any event, the cam 42 ultimately comes into operative engagement with the contactor 47 of switch A. It will be apparent that when the cam 42 moves into operative engagement with the contactor 47 of the switch A during rotation of the cylinder 13 in the "up" direction the system operates as described above in the example where it was assumed that the cylinder 13 was turning in the up direction when the switch 22 was operated. In other words, operation of the switch A by the cam 42 initiates the above described sequence of operations, causing the "up" relay 24 to be energized so that the cylinder 13 is slowed down by the reversed motor M to be stopped by the brake means 48 when the cam 42 operates switch B to deenergize the motor M.

It will be observed that in the above described operations the switch C did not perform any function. The operation of the switch C by the cam 42 during the above described operations having no effect on the control system, the switch C merely being temporarily opened without producing any result. The switch C is incorporated

in the system to assure correct operation in the event the stop switch 22 is operated, to the position illustrated, at a time when the cylinder 13 is turning in the "down" direction and at the particular time when the cam 42 is holding the contactor 47 of switch A in cooperation with the contacts 45 and 46. Assuming that the switch 22 is operated to the position shown at this particular time the circuit to the coil 63 of the relay 21 is completed through the lead 73, the switch C, the lead 71, the outer contacts 45 and 46 of switch A, the lead 72 and the stop switch 22, the other side of the coil 63 being connected in the power line 33 by lead 74. As above described, energization of the coil 63 breaks the circuit through the normally closed contacts 66 and 69 to the up relay 23 and completes a circuit to the coil 29 of the down relay 24 through the contacts 65 and 68 and the leads connected therewith. Accordingly, the "down" rotation of the cylinder 13 continues after the cam 42 has left switch A.

The cylinder 13 continues to turn in the "down" direction and the cam 42 ultimately opens switch C. Opening of switch C breaks the circuit to the coil 63 of relay 21 as switch C is interposed in the line 73 extending from one terminal of the coil. Relay 21 restores to its normal condition where the contacts 66 and 69 are closed to complete the circuit to the coil 28 of the up relay 23 and where the coil 29 of the down relay is deenergized. With the "up" relay 23 energized and the "down" relay 24 deenergized the motor M is reversed to cause the cylinder 13 to rotate in the "up" direction. The cam 42 on the cylinder 13 moves "up" toward the switch A and ultimately operates switch A. This operation of switch A initiates the above described series of operations and the system acts exactly the same as in the example described where the stop switch 22 is operated when the cylinder 13 is rotating in the up direction. The switch C is positioned some distance from the switch A so that the cylinder 13 will have gained suitable momentum or inertia by the time the cam reaches switch A, thus assuring subsequent movement of the cam 42 into cooperation with switch B to stop the cylinder 13, all as described above.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. In combination, a moving element, power means for moving the element, means for reversing the power means, the reversed power means serving to reduce the inertia of the rotating element, means for rendering the power means ineffective in either direction a given time following operation of the reversing means and for holding the elements against movement when the inertia of the element has reached a very low value and before the element has begun reverse movement, and switch means for initiating operation of the reversing means.

2. In combination, a rotatable element, reversible power means for rotating the element, means for reversing the power means operable when the element reaches a given position, the reversed power means serving to reduce the inertia of the rotating element, and means oper-

able following operation of the reversing means for rendering the power means ineffective when the reversed power means has slowed the element to a substantial stop at a given position and before the element begins movement in a reverse direction.

3. In combination, a rotatable element, reversible power means for rotating the element, means for reversing the power means operable when the element reaches a given position, the reversed power means serving to reduce the inertia of the rotating element, a circuit governing the reversing means having a switch operable to condition the reversing means for operation, and means operable following operation of the reversing means for rendering the power means ineffective when the reversed power means has slowed the element to a substantial stop at a given position and before the element begins reverse movement.

4. In combination, a rotatable element, reversible power means for rotating the element, means for reversing the power means, means for putting the reversing means into operation comprising a circuit controlling the reversing means, a switch in the circuit and a part rotatable with the element for operating the switch, and means for discontinuing operation of the power means when the reversed power means has brought the element substantially to a stop and before the element begins reverse movement.

5. In combination, a rotatable element, reversible power means for rotating the element, means for reversing the power means, means for putting the reversing means into operation comprising a circuit controlling the reversing means, a switch in the circuit and a part rotatable with the element for operating the switch, and means for discontinuing operation of the power means when the reversed power means has brought the element substantially to a stop and before the element begins reverse movement comprising a switch operable to deenergize the power means and operable by said part.

6. In combination, an enclosing structure having an opening, an element rotatable in the structure and having an opening adapted to register with the opening thereof, reversible power means for rotating the element, reversing means for causing alternate operation of the element in opposite directions, a relay operable to cause operation of the power means in one direction and then in the other direction, switch means operable to transfer control of the power means from the reversing means to the relay, switch means made operative upon actuation of the first named switch means and operable by movement of the element in either direction to put the relay into operation at a given phase of rotation of the element so that rotation of the element in said other direction slows the element, and switch means made operative with the relay for deenergizing the power means and relay to stop the element where said openings are in communication.

7. In combination with a rotating element and a reversible drive for the element having a normally operative reversing means for causing alternate rotation of the element in opposite directions, control means operable to cause operation of the power means in one direction when the element is in a given rotative position regardless of the direction the element may be rotating, said operation of the power means in said one direction tending to slow down the element in the event the element is turning in the opposite di-

rection, element positioning means operable following operation of the control means to deenergize the power means and control means when the element has continued to turn in said opposite direction to a given position, and means operable to transfer control of the power means from said reversing means to said control and energizing the power means to rotate the element in said one direction until said control comes into operation.

8. In combination with a rotating element and a reversible drive for the element having a normally operative reversing means for causing alternate rotation of the element in opposite directions, control means operable to cause operation of the power means in one direction when the element is in a given rotative position regardless of the direction the element may be rotating, said operation of the power means in said one direction tending to slow down the element in the event the element is turning in the opposite direction, element positioning means operable following operation of the control means to deenergize the power means and control means when the element has continued to turn in said opposite direction to a given position, brake means operated upon actuation of the positioning means for stopping the element, and means operable to transfer control of the power means from said reversing means to said control and energizing the power means to rotate the element in said one direction until said control comes into operation.

9. In combination with a rotating element and a reversible drive for the element having a normally operative reversing means for causing alternate rotation of the element in opposite directions, control means operable to cause operation of the power means in one direction when the element is in a given rotative position regardless of the direction the element may be rotating, said operation of the power means in said one direction tending to slow down the element in the event the element is turning in the opposite direction, element positioning means operable following operation of the control means to deenergize the power means and control means when the element has continued to turn in said opposite direction to a given position, means operable to transfer control of the power means from said reversing means to said control and energizing the power means to rotate the element in said one direction until said control comes into operation, and safety means for preventing continued rotation of the element in said one direction in the event the last named means is operated when the element is in said given position.

10. In combination with a rotating element and a reversible drive for the element having a normally operative reversing means for causing alternate rotation of the element in opposite directions, control means operable to cause operation of the power means in one direction when the element is in a given rotative position regardless of the direction the element may be rotating, said operation of the power means in said one direction tending to slow down the element in the event the element is turning in the opposite direction, element positioning means operable following operation of the control means to deenergize the power means and control means when the element has continued to turn in said opposite direction to a given position, means operable to transfer control of the power means from said reversing means to said control and

energizing the power means to rotate the element in said one direction until said control comes into operation and a safety switch for preventing continued operation of the element in said direction in the event the last named means is operated at the time the element is in said position.

11. In a washing machine, a shell having an opening, a cylinder rotatable in the shell and having an opening, power means for rotating the cylinder in both directions during operation of the machine, and means controlling the power means to cause the cylinder to turn through its inertia in a direction so that its opening moves upwardly to the opening in the shell while the power means is tending to turn the cylinder in the opposite direction and to stop with its opening in register with the opening in the shell regardless of the direction in which the cylinder may be turning when the last named means is put into operation. 20

12. In a washing machine, a shell, a rotatable cylinder in the shell, the shell and cylinder having openings in their side portions, power means for rotating the cylinder, means for reversing the power means for causing alternative rotation of the cylinder in opposite directions, and cylinder stopping and positioning means controlling the power means to turn the cylinder so that its opening moves up to the opening in the shell through its inertia and while the power means is tending to turn the cylinder in the opposite direction to overcome the inertia and then stop the cylinder with the openings in register irrespective of the direction the cylinder may be turning when the stopping and positioning means is put into operation. 15
